AUTOMATIC FIREARM

Ernest C. Neal, Chicago, Ill., assignor, by mesne assignments, to himself and Elmer Brandell, Chicago, Ill.

Application May 23, 1942, Serial No. 444,227

17 Claims. (CL. 89—125)

1

This invention relates to firearms, and more particularly to automatic or semi-automatic recoil operated firearms.

A primary object of the invention is the provision of a firearm having a firing power and destructive effect that is much greater than that of known weapons of comparable size and weight.

A further object is the provision of a firearm having a greatly increased target coverage whereby accurate aiming is not essential to hitting a target and even relatively small and rapidly moving targets are more likely to be hit without accurate aiming.

A further object is the provision of an automatic or semi-automatic recoil operated firearm having a destructive effect and target coverage corresponding to that of firing heavy buckshot from a shot gun while combining therewith the accuracy, range and pattern control of a cartridge or single projectile type of weapon.

A further object is to provide a firearm and firing mechanism therefor which may be incorporated into the form of a relatively light arm, such as a side arm or a rifle, and which may be utilized equally well in a much heavier type of weapon, such as a heavy caliber anti-tank or anti-aircraft gun.

A still further object is the provision of a firearm that is adapted for either sporting, military or police use, and which is more effective in all of these fields than known weapons of like size and type.

Still another object is the provision of a multi-barreled firearm in which a plurality of individual cartridges or shells are simultaneously fired, thereby providing for increased firing power and target coverage while maintaining accuracy in range and pattern control.

A further object is the provision of such multi-barreled firearm which provides for automatically discharging fired cartridge shells and automatically reloading the plurality of barrels during a number of successive firings of the weapon.

A further object is the provision of a multi-barreled firearm in which a single firing pin head, a single breech block and a single firing hammer provide for ejecting used cartridge shells, reloading the barrels, and firing all of the barrels simultaneously.

A further object is the provision of a firearm in which a plurality of readily refillable magazine tubes each adapted to contain a plurality of cartridges are positioned in the base of the weapon in parallelism with the firing axis of the weapon,

2

and provision is made for automatically reloading the firearm from the magazine tubes.

A still further object is the provision of an improved hand grip and support for a revolver or side arm type of firearm.

Still another object is the provision of novel mechanism for effecting the automatic or semi-automatic operation of a multi-barreled firearm.

These and other objects and advantages of the invention will be apparent from the following description, the appended claims and the accompanying drawings.

The drawings illustrate one selected form of the invention, which for purposes of description is shown as being of the side arm or revolver type, and the views therein are as follows:

Fig. 1 is a side elevation of a firearm embodying the invention;

Fig. 2 is a front elevation of the muzzle portion of the firearm shown in Fig. 1;

Fig. 3 is a rear end elevation of the firearm;

Figs. 4a and 4b are complementary views divided along the line 4—4 and together showing a longitudinal vertical section through the firearm, the parts being illustrated in the firing position:

Fig. 5 is a transverse section taken on the line 5—5 of Fig. 4a and shows the firing pin head in firing position with respect to the receiver head and gun barrels;

Fig. 6 is a transverse section taken on the line 6—6 of Fig. 4a and shows the firing pin head in the after-firing position;

Fig. 7 is a transverse section taken on the line 7—7 of Fig. 4a and shows the arrangement of the breech block within the jacket of the firearm.

Fig. 8 is a transverse section taken on the line 8—8 of Fig. 4b and shows the arrangement of the magazine tubes and hammer block within the weapon;

Fig. 9 is a transverse section taken on the line 9—9 of Fig. 4b and also shows the magazine tubes and hammer block;

Fig. 10 is a perspective view of the spool and bearing structure for supporting the barrels at the forward end of the weapon;

Fig. 11 is a perspective view of the receiver head looking from the forward or muzzle end of the weapon;

Fig. 12 is a perspective view of the receiver head looking from the rear or butt end of the weapon;

Fig. 13 is a perspective view of the firing pin head;

Fig. 14 is a perspective view of the breech

block;

Fig. 23 is a perspective view of the extractor bar;

Fig. 24 is a perspective view of the ejector bar;

Fig. 25 is a perspective view of the cartridge pushing and supporting clips carried by the firing pin head;

Fig. 26 is a detail sectional view showing a portion of the gun mechanism with the parts in firing position, the section being taken along the line of 26—26 in Fig. 28;

Fig. 27 is a detail sectional view showing the mechanism of Fig. 26 in its rear-most position after firing of the weapon;

Fig. 28 is a transverse sectional view taken on the line 28—28 of Fig. 27;

Fig. 29 is a top-plan view of the saddle assembly showing the trigger mechanism;

Fig. 30 is a detail view of the support for the magazine assembly;

Fig. 31 is an elevational view of the forward end of the magazine support shown in Fig. 30;

Fig. 32 is a transverse sectional view taken on the line 32—32 of Fig. 30;

Fig. 33 is a detail view, partly in section, of the removable tubes and end support forming a part of the magazine assembly;

Fig. 34 is a detail view of a portion of the trigger mechanism;

Fig. 35 is a detail view of a portion of the trigger mechanism illustrated in Fig. 34; and

Fig. 36 is a diagrammatic view illustrating a typical target pattern for the plurality of projectiles fired by the firearm and shows the manner in which the projectiles disperse to cover a target of desired area at a desired range.

Referring to the drawings, the illustrated firearm comprises a cylindrical shell or jacket 10 providing a support for a plurality of barrels 11. As indicated in Fig. 2, the weapon is shown as having five barrels 11 arranged in a circle concentric with the longitudinal axis of the jacket 10 and equally spaced around this circle. Front and rear sights 12 and 13 are secured to the top portion of the jacket to provide for accurate aiming of the firearm when desired, and a saddle 14 is removably attached to the underside of the jacket by means of screws 15.

The saddle 14 carries a hand grip 16 and a trigger guard 17 which may be integrally connected with the hand grip and saddle as illus-

trated. A trigger 18 extends downwardly into the opening of the trigger guard 17 and is adapted to be engaged by the forefinger of the person firing the gun while the hand of the firer grips around the hand grip 16, as indicated by dashed lines in Fig. 1. A manually operable lever 19 also extends outwardly of the jacket 10 through a slot 20 and is slideable within the slot to provide for manually loading and unloading the weapon, as will be hereinafter more fully described.

The jacket 10 extends a substantial distance rearwardly of the hand grip 16 to provide a magazine chamber in the rear portion of the weapon, and an additional means for supporting and steadyng the side arm illustrated during firing thereof is provided on this rearwardly extending portion of the jacket. As shown in Figs. 1 and 3, this means comprises a downwardly extending strap or plate member 25 which is secured to the jacket 10 by screws 26 and is provided at its lower end with a hook-shaped portion 27 adapted to engage around and provide a rest for the forearm of the firer of the weapon. The hook-shaped portion 27 of the arm rest 25 is preferably covered with sponge rubber or the like, as indicated at 28, and engages the forearm of the operator at a substantial distance in rear of the wrist, as is also illustrated by dashed lines in Fig. 1.

The arm rest thus engages the firer's arm at a relatively rigid or stiff portion thereof and assists in supporting and steadyng the firearm against downward movement and lateral wavering. To still further assist in supporting and steadyng the illustrated weapon during firing, a second hand grip 29 of tubular shape is secured to the gun jacket 10 adjacent the arm rest 25 and extends downwardly at a side of the weapon opposite to the arm support. The hand grip 29 is adapted to be grasped by the other hand of the firer of the weapon, as is also indicated by dashed lines in Fig. 1, and together with the hand grip 16 and arm rest 25, provides a very firm and steady support for aiming and firing a side arm type of weapon.

The firearm of the present invention is of the automatic or semi-automatic recoil operated type, and to provide for this action the plurality of barrels 11 are slidably supported in the jacket 10 for limited longitudinal movement therein. Referring to Figs. 4a and 10, a barrel supporting spool 35, comprising a pair of spaced circular supporting members 36 and 37 and a hollow tubular portion 38, is inserted within the forward portion 55 of the jacket 10 and provides a bearing for slidably supporting the plurality of barrels 11. The supporting member 36 of the spool is externally threaded, as indicated at 39, and this threaded portion is adapted to engage an internally threaded portion provided at the forward end of the gun jacket 10, as shown in Fig. 4a. The supporting spool 35 is maintained in fixed position within the jacket 10 by screws 40 which extend through the jacket 10 and thread into the supporting members 36 and 37 of the spool.

The plurality of barrels 11 are slidably received within a plurality of aligned openings 41 and 42 provided in the members 36 and 37 of the supporting spool 35, and the member 36 is provided with integrally extending bosses 43 at each of the openings 41 to provide additional bearing support for the barrels. When the spool 35 is received in position within the jacket 10, the outer end of the supporting member 36 provides a plug for closing the open end of the jacket 10.

The barrels 11 are externally threaded at their inner ends, as indicated at 48 in Fig. 1, and are screwed into a receiver head 46, Figs. 4, 11, and 12, which provides a unitary rigid supporting assembly for the plurality of barrels. The receiver head 46 is slidably received within the gun jacket 10 in rear of the supporting member 37 of spool 35, and the entire barrel assembly, including the plurality of barrels 11 and the head 46, are adapted to move rearwardly under recoil action when the weapon is fired. A centrally positioned stem member 47 extends forwardly of the receiver head 46 and is slidably received within the hollow tubular portion 38 of the spool member 35.

A spring 48, Fig. 4, is also mounted within the hollow portion 38 of the spool and is connected at one end to the forward end of the stem member 47, as indicated at 49. The opposite end of spring 48 is connected to an eyebolt 50 which extends through a nipple 51 threaded into the spool portion 38 and is threadably received within a cap nut provided on the exterior side of the nipple. The spring 48 opposes rearward movement of the receiver head and barrel assembly and provides for return of the assembly to the firing position shown in Fig. 4a after the rearward movement thereof under recoil action. The eyebolt 50 and nut 52 provide for adjusting the tension of spring 48, and this tension is so adjusted that the receiver head and barrel assembly will move rearwardly at a high velocity when the gun is fired, but will be returned under action of the spring 48 when the assembly has reached the end of its recoil movement.

The movement of the receiver head 46 and barrel assembly in the rearward and forward direction is positively limited by a stop pin 53 which is mounted in a lug 54 provided on the spool member 37 and is received within a slot 55 provided in the stem member 47 of the receiver head. The stop pin 53 passes through an opening 56 provided in the hollow member 38 of the spool 35, and a suitable opening (not shown) is provided in the jacket 10 to permit insertion and removal of the stop pin upon assembly and disassembly of the gun.

A friction brake is also provided to assist in slowing down the receiver head and barrel assembly and in bringing the assembly to a stop at the end of its rearward and return movements. As shown in Figs. 1, 6, 16, 17, and 29, this brake comprises a dog 60 pivotally mounted in the saddle 14, as indicated at 61, and pressed against the underside of the receiver head 46 by a spring 62. To provide for frictional engagement of the dog 60 with the receiver head 46 throughout the entire extent of its movement, the receiver head is provided with a forwardly extending arm 63 against which the dog presses, as clearly indicated in Fig. 16.

An upstanding lug 64 is also provided on the dog 60 and is adapted to be received within a notch 65 provided in the receiver head 46 when the head is at its forward or firing position, for a purpose to be hereinafter more fully described. The lug 64 and notch 65 are provided with cooperating inclined surfaces, as shown, to effect camming of the lug out of the notch when the gun is fired and the receiver head moves rearwardly under recoil action. A notch or groove 66 is also provided in the lower portion of the spool member 37 for slidably receiving the forwardly extending arm 63 of the receiver head.

A firing pin head 70, best shown in Fig. 13, is mounted within the jacket 10 in rear of the re-

ceiver head 46 and is adapted to be received and locked within the receiver head when the parts are in firing position. The firing pin head is of generally cylindrical configuration and slidably fits within a circular recess 71 provided in the rear portion of the receiver head 46. The firing pin head is releasably locked within the receiver head at the time that the firearm is fired by means of a pair of diametrically opposed locking lugs 72 which are provided on the firing pin head and engage behind locking flanges 73 provided on the receiver head. The locking flanges 73 are spaced apart at their adjacent ends to provide notches or openings 74 forming gates through which the locking lugs 72 are adapted to pass when the head 70 is rotated to align the lugs with the notches. Locking of the firing pin head within the receiver head is effected by rotating the head 70 through a predetermined angle, approximately 36° in the illustrated embodiment, to engage the locking lugs 72 behind the flanges 73 as illustrated in Fig. 5 of the drawing, and unlocking is effected by rotating the firing pin head in the opposite direction to align the lugs 72 with the notches 74 as shown in Fig. 6.

A plurality of firing pins 75, one for each of the barrels 11, are mounted on the firing pin head 70 and are so positioned that when the head 70 has been rotated to its predetermined locked position within the receiver head, each of the firing pins is in direct alignment with one of the gun barrels, as is also clearly shown in Fig. 5. The firing pins 75 are slidably mounted in sleeves 76 threaded into recesses provided in solid portions of the head 70 and, as shown in Fig. 4a, comprise a pin portion 77, an enlarged portion 78, and a head 79. Coil springs 80 adapted to be compressed between the bottom of the recesses in the head 70 and the enlarged portions 77 of the pins provide for normally maintaining the head portions 79 of the pins in an outwardly extended position with respect to the rear face of the firing pin head. Upon firing of the weapon the heads 79 are driven inwardly against the force of the springs 80 to strike the pin portions 77 against the firing caps of cartridges received in the barrels 11. The inner ends of the barrels 11 extend substantially flush with the inner face of the receiver head recess 71 to receive the cartridges, and with the firing pin head in firing position, solid metal portions of the head are positioned behind each of the cartridge shells, as illustrated in Figs. 4a and 5 of the drawings.

A relatively heavy breech block 85 is positioned within the gun jacket 10 in rear of the firing pin head 70 and is operatively connected to the firing pin head by means of a pin 86 which is carried by the breech block and extends through a pair of spirally shaped cam slots 87 provided in a stem 88 extending rearwardly from the firing pin head. The stem 88 is slidably received within a central bore 89 provided in the breech block 85 and the bore 89 provides a bearing for rotatably and slidably mounting the firing pin head on the breech block. The breech block is mounted for sliding movement within the jacket 10, but is prevented from rotating about the longitudinal axis of the fire arm by means of a pair of keys 90 secured to the jacket 10 and slidably received within elongated grooves or slots 91 provided in the outer surface of the breech block. An elongated stem 92 extends rearwardly of the breech block 85 and is adapted to compress a coil spring 93 positioned adjacent the rear portion of the weapon. The spring 93 provides for

returning the breech block to its forward firing position after the block has reached a predetermined limit of rearward movement.

When the weapon is fired, the recoil action causes the receiver head 48 and the barrel assembly to move rearwardly at a high velocity and the receiver head carries the firing pin head which is locked therein rearwardly with it. This rearward movement of the receiver and firing pin heads is transmitted to the breech block 85 and causes the breech block to also travel rearwardly at a high velocity, the pin 86 carried by the breech block being positioned at this time adjacent the forward ends of the spiral cam slots 87 provided in the firing head stem 88. When the receiver head and barrel assembly have reached the limit of their rearward movement, as determined by the stop pin 53 and the length of the slot 55, these parts come to a momentary stop but the breech block continues to move rearwardly due to the momentum stored therein by the recoil action of the gun.

As the breech block continues its rearward movement the pin 86 moves along the cam slots 87 and causes the firing pin head 70 to rotate within the receiver head in a counter-clockwise direction as seen in Figs. 5, 6, and 13. The relative length and curvature of the cam slots 87 is such that when the pin 86 has reached the rearward end of the slots the firing pin head will have been rotated through an angle sufficient to bring the locking lugs 72 into alignment with the slots or openings 74 in the locking flanges of the receiver head, as shown in Fig. 6. At this time the parts are in the relative positioning illustrated in Fig. 16.

As the breech block continues to move still further rearwardly due to its momentum it now pulls the firing pin head with it, the locking lugs 72 passing through the slot 74 and the firing pin head being withdrawn from the recess of the receiver head. The breech block and firing pin head thereafter move as a unit until the head 70 has been again inserted within the receiver head as will be hereinafter described. As soon as the firing pin head has been freed from its locking engagement with the receiver head, the spring 48 causes the receiver head and barrel assembly to return to their normal forward position illustrated in Fig. 4a.

A means is provided for extracting the used cartridge shells from the barrels of the gun and for ejecting the used shells from the weapon during the rearward movement of the breech block and firing pin head. The rearward movement of the breech block and firing pin head under the recoil action of the weapon is also utilized to effect the picking up of a fresh cartridge for each of the gun barrels from the magazine positioned in the rear portion of the gun.

To effect the extraction of the used cartridge shells from the gun barrels, a plurality of extractor bars 95, one for each barrel, are slidably mounted in grooves 96 provided on the outer surface of the breech block 85 and extend forwardly over the outer cylindrical surface of the firing pin head. A downwardly extending nose or hook 97 is provided on the forward end of each of the extractor bars and is adapted to engage against the forward side of the conventional bead which is provided at the base of the cartridge shell as is clearly shown in Figs. 4, 16, and 17. A downwardly extending lug 98 is also provided on each of the extractor bars 95 and is

adapted to be received within a circular groove or slot 99 (see Fig. 13) provided in the outer cylindrical surface of the firing pin head. The extractor bars 95 are thus locked to the firing pin head and move rearwardly and forwardly with movement of the head.

Thus as the breech block and firing pin head travel rearwardly due to the recoil action of the gun the extractor bars likewise move rearwardly and cause the used cartridge shell to be extracted from the gun barrels as indicated in Fig. 16. During the rotation of the firing pin head to effect unlocking thereof from the receiver head the lugs 98 of the extractor bars slide within the circular slots 99 of the firing pin head. The extractor bars 95 are more particularly illustrated in Fig. 23 and as shown therein are provided with outwardly inclined toe portions 100 which cooperate with inclined portions of the breech block grooves 96 (see Fig. 14) to maintain the extractor bars in proper positioning within the breech block grooves.

The breech block 85 and the firing pin head 70 are also each provided with a plurality of openings 105 and 106, respectively, which extend throughout the length of the breech block and firing pin head, there being one opening 105 and 106 for each of the gun barrels 11. The openings 105 in the breech block are positioned in direct alignment with the gun barrels 11, and the openings 106 in the firing pin head are so positioned that each of these openings will also be in direct alignment with the gun barrels as well as with the openings 105 of the breech block when the head 70 has been rotated to its unlocked position illustrated in Fig. 6. A plurality of magazine tubes 107, one for each of the gun barrels 11, are supported on the rear portion of the weapon and are arranged in direct alignment with the gun barrels as well as the openings 105 in the breech block and the openings 106 in the firing pin head when the latter has been rotated to its unlocked position of Fig. 6. The magazine tubes 107 are adapted to extend through the openings 105 in the breech block and into the opening 106 in the firing pin head when the block and head move rearwardly under the recoil action, and the openings 105 and 106 are of a size to permit the entry of the tubes 107 therein.

As more particularly shown in Figs. 18, 19 and 22, a pair of ejector bars 110 are secured to each of the magazine tubes 107 and extend a predetermined distance into the openings 105 of the breech block 85. During the rearward movement of the breech block and firing pin head the ejector bars 110 pass through the openings 106 of the head 70 and engage against the bottom of the empty cartridge shells at an edge thereof opposite to the point where the bead of the shell is engaged by the hooked nose 97 of the extractor bars 95. At the time of the engagement of the ejectors 110 with the cartridge shells, the shells have been entirely withdrawn from the gun barrels and as the extractor bars continue to move rearwardly with the firing pin head the shells are caused to swing outwardly with respect to the axis of the weapon and to be ejected through suitable ejection openings 111 provided in the outer jacket 10 of the gun. This operation of the gun in ejecting the used cartridge shells is indicated by the dotted lines in Fig. 17. The portion of the saddle 14 which underlies the ejection openings 111 for the two lower barrels of the weapon is provided with openings 112, corresponding to the openings 111, as shown in Fig. 5.

to permit ejection of the used shells from the lower barrels.

The fresh cartridge to be picked up by the firing pin head for loading into each gun barrel is supported at the forward end of the magazine tubes 107 by means of a pair of spring clips 115 (see Fig. 22) which are arranged in planes substantially at right angles to the ejector bars 110 and comprise extensions of the tubes 107. The spring clips 115 are arcuate in transverse cross-section to engage around the sides of the fresh cartridges and are provided with openings adjacent the end of the tube 107 into which spring members 116 secured to the clips 115 are adapted to extend. The spring members 116 are suitably bent to provide shoulders 117, see Figs. 19 and 22, which engage against the bottom of the cartridge shell after the cartridge has been received within the clips 115. The spring members 116 are readily sprung outwardly, however, by the fresh cartridge as it is moved forwardly from within the magazine tube 107 to permit the bottom of the cartridge to slide past the shoulders 117.

To provide for picking up the fresh cartridges and loading them into the gun barrels a pair of spring clip members 120 are secured within each of the openings 106 of the firing pin head 70 and are adapted to engage in rear of and around the bottom bead on the cartridge to support the cartridge adjacent the forward face of the head 70 and load the cartridge into the barrels upon return forward movement of the firing pin head. As best shown in Figs. 18 and 21, the pushing and supporting clips 120 are arranged substantially at right angles to the spring clips 115 and are adapted to pass between the ejector bars 110 and the clips 115. Referring to Figs. 18 and 25 each of the clips 120 comprises a head portion 121 which is secured to the firing pin head 70 within the openings 106 by means of a spring portion 122 normally urging the head 121 inwardly toward the axis of the opening. Each of the head portions 121 is provided with bead engaging portions 123 which engage in rear of and around the cartridge bead, as above described and shown in Fig. 18, to clamp the cartridge between the oppositely disposed spring clips 120 under action of the spring portions 122.

The clips 120 are mounted within grooves 124 provided in the firing pin head adjacent the openings 106 (see Fig. 13), and during the rearward movement of the head 70, the resilient clips are adapted to be sprung to an out-of-the-way position within these grooves by engagement of the fresh cartridges with the spring portions 122 of the clips, thereby permitting the clips to slide past a fresh cartridge supported within the clip members 115 of the magazine tubes 107. Suitable recesses 125 are also provided in the head 70 for receiving the head portions 121 of the clips. As soon as the head 70 has moved sufficiently far in a rearward direction to clear the rear of the fresh cartridges, the clips 120 spring inwardly again under action of the springs 122 to clamp the bead of the cartridge within the clip portions 123, as above described. A fresh cartridge is thus supported on the forward face of the firing pin head in direct alignment with each of the gun barrels 11. Inward movement of the clips 120 under action of the springs 122 during rearward travel of the firing pin head prior to the engagement of the clips with the fresh cartridges, is limited by a flanged shoulder 126 provided on each of the head portions 121 of the

clips and cooperating with a corresponding shoulder provided on the firing pin head adjacent the recesses 125.

The rearward travel of the breech block 85 and firing pin head 70 is definitely limited by fixed stop 130, Figs. 4b and 17, secured to the outer jacket 10 and against which the rearward face of the breech block engages. The spring 93, which is compressed during the rearward movement of the block and head, provides for slowing down these parts, and cushions the force with which the block strikes at stop 130. The stop 130 is so positioned that the clips 120 on the head 70 will have passed completely over the fresh cartridges and engaged the bead at the rear ends thereof before the block and head are brought to a complete stop. Fig. 17 illustrates the relative positioning of the parts at the instant that the breech block and firing pin head have been brought to rest by the stop 130, and the clips 120 on the firing pin head have picked up the fresh cartridge from the magazine tube 107.

As soon as the rearward movement of the block and head has been arrested by the stops 130 and a fresh cartridge has been picked up by each of the pairs of spring clips 120, the spring 93 provides for returning the breech block and firing pin head to the forward firing position. The forward movement of the breech block 85, under action of the compression spring 93, is transmitted to the firing pin head 70 by means of a coil spring 135 and the engagement of the pin 86 with the sides of the cam slots 87 provided in the stem 88 of the firing pin head. The spring 135 is compressed between a cup-shaped member 136 threaded into the rear end of the stem 88 and the end of the hollow bore 89 provided in the breech block 85, as clearly shown in Figs. 16 and 17. A headless screw 137 threads into the end of the bore 89 and is received within the coils of the spring 135 to properly position the spring within the bore. As the head 70 carrying the fresh cartridges thereon moves forwardly, the ends of the ejector bars 110 are flexed downwardly by the passage of the cartridges thereover. To assist in this action the bars 110 are made from a spring material and are joined to the tubes 107 by portions of reduced thickness as indicated at 138 in Figs. 18 and 24.

After the firing pin head 70 and breech block 85 have moved forwardly a distance sufficient to load the cartridges into the gun barrels and insert the head 70 within the recess 11 of the receiver head 46, the forward movement of the head 70 is arrested and continued movement of the breech block under action of the spring 93 causes the pin 86 to move forwardly in the cam slots 87 to rotate the firing pin head to its locked position of Fig. 5 in which the locking lugs 72 are engaged behind the flanges 73 of the receiver head. The spring 135 permits the relative movement between the breech block and the firing pin head necessary to effect the locking rotation of the firing pin head by forward movement of the breech block.

The openings 106 in the firing pin head 70 are maintained in proper alignment with the magazine tubes 107 and the gun barrels 11 during the rearward and forward movement of the head by a latching means which is carried by the breech block 85 and locks the head 70 against rotation during its rearward and forward travel. Referring to Figs. 26 and 27, this means comprises a latching lever 140 pivotally mounted in the breech block 85 at 141 and having forwardly and

rearwardly extending arms 142 and 143 operable within a slot 144 provided in the breech block. The arm 142 carries a latching finger 145 which is adapted to move into a slot 146, see Fig. 13, provided on the end of the stem member 88 of the firing pin head 70 after the breech block has moved rearwardly with respect to the head 70, a distance sufficient for effecting unlocking rotation of the firing pin head. The angular arrangement of the slot 146 on stem 88 is such that when the firing pin head 70 has been rotated to its unlocked position by movement of the breech block relative to the head, in which position the openings 106 of the head are in alignment with the barrels 11 and magazine tubes 107 and the lugs 72 are in alignment with the opening 74, the slot 146 will be in a proper angular position to receive the latching finger 145. A spring 147 positioned within a recess provided in the breech block and compressed against the end of the lever arm 143 provides for resiliently urging the latching finger 145 in a downward direction to effect its engagement with the slot 146 and the stem member 88.

The lever arm 142 normally rides on the top of the stem member 88, as shown in Fig. 26, and maintains the latching finger 145 in a raised position against the action of the spring 147. The head 70 is thus free to rotate under action of the pin 86 in the slots 87 as the breech block moves rearwardly relative to the head upon firing of the weapon. As soon as the relative movement between the breech block and firing pin head is sufficient, however, to free the firing pin head from the receiver head and align the openings 106 with the gun barrels and magazine tubes, the finger 145 drops into the slot 146 under action of spring 147 and the head and block thereafter move together as a unit in the manner hereinabove described with the head locked against further rotation by the lever 140. The downward travel of the latching finger 145 into locking engagement with the slot 146 is limited by engagement of the lever arm 143 with the jacket 10 of the weapon, as shown in Fig. 27, which illustrates the parts after the head and block have been locked together by the latching lever.

Upon return movement of the breech block and firing pin head in a forward direction under action of the spring 93 the latch 140 is released from engagement with the slot 146, to permit locking rotation of the firing pin head, by means of a stationary cam 148 which is fixedly secured to the jacket 10 of the gun. As shown in Fig. 26, which illustrates the parts in the firing position of the weapon, the cam 148 engages the end of lever arm 143 and cams it downwardly against the action of spring 147 to move the latching finger 145 to its raised position in which the lever arm 142 rides on the outer surface of the stem 88. The positioning of the cam 148 is such that it engages the lever arm 143 and effects unlatching of the lever 140 at the instant when the firing pin head has been fully inserted within the receiver head and is ready to be rotated into locking engagement with the receiver head upon further forward movement of the breechblock.

The magazine tubes 107 are rigidly mounted in the rear portion of the weapon by means of a supporting spool 155, Figs. 4b and 30, comprising a hollow central tube 156 and three spaced supporting members 157, 158, 159 adapted to fit within the jacket 10 of the gun and engage the inner wall thereof. The spool 155 is normally

maintained in fixed positioning within the jacket 10 by means of screws 160 which extend through the jacket and thread into the supporting members 157, 158, and 159. The supporting member 157 is positioned at the forward end of the central tube 156 and provides the stop 130 which limits the rearward movement of the breechblock 85, as described above. The spring 93, which is compressed by the rearward movement of the breechblock and provides for returning the breechblock and firing pin head to the forward firing position after a reloading operation, is positioned within the hollow interior of the tube 156, as shown in Fig. 4b, and is compressed between a block 161 slidably mounted within the tube 156 and a fixed block 162 which is threaded into the tube at the rear end thereof. The rearwardly extending stem member 82 of the breechblock is slidably received within the forward end of the tube 156 and is provided with a reduced portion 163 which fits within a recess provided in the sliding block 161.

Each of the members 157, 158, and 159 are provided with aligned openings 165 through which the magazine tubes 107 extend. The tubes 107 are press-fitted into the openings 165 or are otherwise secured to the members 157, 158, and 159 so as to be rigidly supported by the spool 155 in proper spaced position within the rear portion 30 of the weapon. Additional openings 166 may also be provided in the member 157, 158, and 159 to decrease the weight of the supporting spool.

Each of the magazine tubes 107 is adapted to receive and support a plurality of cartridges arranged in end-to-end relationship, as shown in Figs. 4a and 4b. In the illustrated embodiment nine cartridges are adapted to be supported by each of the magazine tubes. To provide for successively feeding the cartridges forwardly to the spring members 115 where they are adapted to be picked up by the firing pin head during the reloading operation hereinabove described, a plurality of tubes 170 are rigidly supported in an end plate 171, Figs. 4b and 33, and are adapted to be telescopically received within the fixed tubes 107 as shown in Figs. 4a and 4b. A coil spring 172 is positioned within each of the tubes 170 and is adapted to be compressed between the end plate 171 and a plunger 173 slidably mounted within each of the tubes. The plungers 173 are adapted to engage against the bottom of the rearmost cartridges supported within the magazine tubes 107 when the tubes 170 are inserted within the tubes 107 and provided for urging the cartridges in the forward feeding direction under action of the springs 172.

Each of the springs 172 and plungers 173 thus provide for successively feeding a fresh cartridge to the spring fingers 115 mounted at the forward end of each of the tubes 107 each time that a cartridge formerly supported within these fingers is removed by the firing pin head. The cartridge is prevented from being pushed out of the spring fingers 115 until it is picked up by the clips 128 of the firing pin head by means of offset shoulder portions 174, Fig. 22, which are provided on the spring members 115 and engage the forward edge of the bead on the cartridge shell. To provide for assuring that the last cartridge will be advanced into proper positioning within fingers 115 the plungers 173 are mounted within the ends of auxiliary sleeves 175 which are slidably received within the tubes 170 and provide for extending the plungers outwardly beyond the normal ends 70 of the tubes 170 as clearly shown in Fig. 33. A

pin 176 limits outward movement of the sleeve 175. A latch 177 normally provides for attaching the end plate 171 to the jacket 10, and a knob 178 provided on the end plate facilitates the removal and insertion of the inner tubes 170 during refilling of the magazine.

The plurality of barrels are simultaneously fired by means of a sliding hammer which engages the rear face of the breech block 85 and forces the breech block against the plurality of firing pins 75 mounted in the firing pin head 70. Referring to Figs. 4b, 8, 9, 15, and 29 the hammer comprises a block 180 which is slidably mounted in a longitudinally extending guideway 181 provided in the saddle member 14. The hammer block 180 is maintained in its guideway by outwardly extending feet or flanges 182 on the block which slide within grooves 183 provided on the saddle 14. The upper surface of the hammer block is provided with suitable grooves 184, Figs. 8, 9 and 15, which permit the block to slide freely beneath the two lowermost magazine tubes 107. The forward supporting member 157 of the magazine spool 155 is also cut away at its lower edge, as clearly shown in Figs. 30 and 31, to permit the block 180 to slide thereunder.

The block 180 is urged in a forward direction by means of a coil spring 185 which is compressed between the hammer block and the supporting member 159 provided on the spool 155 at the rear end of the weapon. The spring 185 is mounted within a tube 186 supported by the spool members 158 and 159 and has its forward end received within a suitable recess provided in the rear portion of the hammer block 180. A rod 187 threaded into the hammer block extends rearwardly from the block and provides a guide for the spring during sliding movement of the hammer block.

The hammer 180 is normally latched in a rearward firing position as illustrated in Figs. 4b and 17 by means of a trip lever 188 having a rearwardly extending arm 189 adapted to engage the forward end of the hammer block adjacent the lower side thereof and lock the block in the rearward position. In this position of the hammer the spring 185 is highly compressed, whereby the hammer block is moved forwardly at high velocity upon release of the latch 189 and strikes the breech block 85 with a sharp blow. This in turn causes the breech block to strike a sharp blow against the firing pins 75 carried by the head 70, thereby to fire simultaneously the plurality of barrels 11.

The trip lever 188 is pivotally mounted on the saddle 14 as indicated at 190, Figs. 4b, 17 and 29, and is adapted to be moved about this pivot by the trigger 18 to release the latching arm 189 from engagement with the forward face of the hammer block 180. For this purpose the trip lever is operatively connected to the trigger by means of a pin 191 which is carried by the trigger and extends into slotted openings 192 provided in forwardly extending forked arms 193 of the lever 188, Figs. 4a, 16, 17 and 29. The trigger 18 is pivotally mounted on the saddle 14 as indicated at 194 and the slotted openings 192 of the lever 188 are so arranged that the pin 191 of the trigger engages the tops of the openings and swings the forwardly extending portion of the trip lever upwardly upon rearward movement of the trigger finger. The rearwardly extending latch finger 189 is thereby caused to move downwardly to release the sliding hammer block 180.

The trigger 18 is normally maintained in the forward position illustrated by means of a spring

188 which engages beneath a forwardly extending arm 186 of the trigger. An upstanding lug 197 is also provided on the trigger and provides for positively returning the trigger to its forward position immediately after firing of the firearm, thereby to assure that the latching arm 189 will be in proper position to lock the hammer block 180 in its retracted position upon return movement of the hammer block. The hammer block is returned to its rearward firing position by the rearward movement of the breech block 85 under recoil action of the firearm, as clearly illustrated in Fig. 17. The slotted openings 192 in the trip lever 188 are enlarged as illustrated, to permit the latching arm 189 of the lever to move downwardly during return movement of the hammer block although the trigger 18 has been returned to its forward position. A spring 198 interposed between the trigger 18 and the lever 188 provides for urging the latch arm 189 upwardly when the trigger is in its forward position. The arm 189 thus moves upwardly under action of spring 198 to lock the hammer 180 as soon as the hammer block has been moved to its rearward position by the breech block 85.

The upstanding lug 197 on the trigger is operated to return the trigger 18 to its normal forward position by means of a downwardly extending lug or rib 199 provided on the breech block 85. With the parts in the firing position illustrated in Fig. 4a the lug 199 is in front of the trigger lug 197 and a space is provided beneath the breech block to provide for upward and forward movement of the trigger lug 197 upon rearward pull on the trigger finger to effect firing of the firearm. Immediately after firing of the weapon, however, a tapered cam surface 199' on the rearward side of the lug 199 engages the trigger lug 197 and causes the trigger to be returned to its forward position.

The trigger lug 197 together with a pair of arms 200 which are pivotally connected to the saddle 14 as indicated at 201 and which are pivotally connected to a pin 202 rigidly carried by the trigger arm 196 also provide for maintaining the trigger in its forward position until the breech block 85 and firing pin head 70 are again in firing position. For this purpose a downwardly and longitudinally extending rib 203 is provided on the under side of the breech block and is adapted to engage the trigger lug 197 to prevent upward and forward movement of the lug as illustrated in Fig. 16. A spring pressed plunger 205, Figs. 34 and 35, having a notch 206 and a head 207 is also mounted in each of the arms 200. The pin 202 is provided with a flat side 208 adapted to engage the under side of the plunger 205 when the plunger is extended as illustrated in Fig. 34 to prevent movement of the trigger about its pivot 194 during engagement of the surface 208 with the plunger 205.

The head 207 of the plunger 205 is adapted to be engaged by the face 210 of lug 199 on the breech block 85. Therefore, as the breech block 85 moves forwardly it moves the plunger 205 inwardly against the action of the plunger spring 209 and as the breech block moves rearwardly it disengages the head 207 and permits the plunger to be extended by the spring 209. The notch 206 is so positioned that it overlies the pin 202 when the plunger 205 is moved inwardly by engagement of the breech block with the plunger head 207 as illustrated in Fig. 35. The position of the notch 206 is also such that it overlies the pin 202 only 75 when the parts of the firearm are in firing posi-

tion. The pin 202 is thus free to turn within the notch 206 when the firearm parts are in firing position, but the trigger 18 is restrained against rearward movement when the notch 206 moves out of alignment with the pin 202.

The arms 200 also provide for maintaining a predetermined spacing between the breech block 85 and the firing pin head 70 upon return movement of the block and head to prevent premature firing and also to provide for striking the firing pins 75 a sharp blow upon engagement of the hammer block 180 with the breech block. For this purpose the rearward portions of the arms 200 and the plungers 205 carried by said arms extend upwardly on each side of the rib 203 of the breech block when the trigger 18 is in its forward position and are adapted to engage the forward face 210 of the lug 199 on the breech block. Since the trigger 18 is returned to its forward position, by the cam surface 199' on lug 199, immediately after firing of the weapon the arms 200 provide a positive stop for the breech block upon its forward movement under action of spring 93. Return of the notch 206 into alignment with the pin 202 and release of the trigger 18 by the plunger 205 are accomplished upon the return of the breech block to the position shown in Fig. 4a as the face 210 of the lug 199 engages the plunger 205 and returns it to the position shown in Fig. 35. Upon rearward pull on the trigger finger to fire the weapon, however, the arm 196 and pin 202 move the arms 200 downwardly to permit the breech block to strike the firing pins upon engagement of the breech block by the firing hammer.

A safety lock is also provided to prevent accidental firing of the loaded firearm. This lock comprises a plunger 215 which is slidably mounted in the saddle 14 and is keyed to the saddle to prevent rotation thereof. The plunger 215 is of generally circular cross-section but is provided with a notched-out or cut away portion 216. The plunger is arranged beneath the rearwardly extending end of the hammer latching arm 189 and is provided with outwardly extending finger engaging portions 217, Fig. 8. So long as the notched portion 216 of the plunger lies beneath the latch 189, the latch is free to be released by movement of the trigger 18. When, however, the circular portion of the plunger 215 is moved beneath the latch arm 189 by pressing against one of the finger portions 217, the trip lever 188 and trigger 18 are locked against movement to release the latching arm 189.

The firearm, as thus described, operates as follows: The plurality of barrels 11 are mounted in the jacket 10 for limited sliding movement under recoil action. A receiver head is locked to the barrels for limited unitary movement therewith and provides for receiving a firing pin head mounted for both rotary and longitudinal sliding movement. The firing pin head contains a firing pin for each barrel of the weapon, and when in firing position, is locked within the receiver head with the firing pins in operative positioning with respect to the barrels. A relatively heavy breech block is slidably mounted in rear of the firing pin head and is operatively connected to the firing pin head by means of a pin and a spirally-shaped cam slot. The rearward movement of the receiver head and firing pin head during recoil also imparts a rearward motion to the breech block. After the barrels and receiver head have reached the limit of their rearward recoil movement, the breech block continues its rearward movement due

to the momentum imparted therein and effects controlled rotation of the firing pin head within the receiver ring by means of the aforementioned pin and spiral connection between the breech block and the firing pin head. This rotation of the firing pin head provides for unlocking the head from the receiver head and also provides for aligning an opening of predetermined size with each of the gun barrels.

10 After the firing pin head has been released from the receiver head, the plurality of barrels and the receiver head are returned as a unit to the normal forward position by means of a spring, and simultaneously therewith, the breech block 5 continues to travel rearwardly due to its momentum and pulls the firing pin head in a rearward direction therewith. During this rearward movement of the breech block, a plurality of extractors carried by the breech block provide for withdrawing the used cartridge shells from the barrels and cooperate with fixed ejectors to eject the used shells through suitable openings provided in the outer jacket of the weapon. A fixed stop limits the rearward movement of the breech block and firing pin head, and at this point the head picks up a fresh cartridge for each of the barrels of the weapon from magazine tubes arranged in direct alignment with the gun barrels; these fresh cartridges passing through the above mentioned openings in the head and being supported on the head at the forward face thereof.

35 The firing pin head and breech block are then moved forwardly by means of a compression spring and load the fresh cartridges into the respective barrels. Upon continued forward movement of the breech block under action of the compression spring, the pin and cam slot connection causes the firing pin head to rotate in a direction opposite to that of when the gun is fired and effects relocking of the head within the receiver head. The degree of rotation of the firing pin head is such that solid metal is positioned behind each of the cartridge shells and the firing pins are moved to operative positioning with respect to the cartridges as above described.

40 A firing hammer is slidably mounted in the weapon in rear of the breech block, and is normally urged in a forward direction by a relatively strong compression spring. This hammer is moved rearwardly by the rearward movement of the breech block during reloading and is locked in a rearward position by means of a trigger controlled latch. After the firing pin head has been returned to its normal forward position and has been locked within the receiver head, the trigger 50 can be operated to release the hammer latch and permit the hammer to be moved forwardly at a relatively high velocity by means of its compression spring. The hammer strikes the rear portion of the breech block with considerable force and forces the breech block against the firing pins carried by the firing pin head to effect operation thereof and firing of the weapon. Suitable locking means is provided for preventing operation of the trigger until the firing pin head 60 has been locked in operative position within the receiver head.

65 A stop means operated by the trigger also normally limits the forward travel of the breech block during reloading of the weapon to provide a small spacing between the breech block and the firing pin head and thus prevent premature firing of the cartridges. Upon operation of the trigger this stop means is released from its engagement with the breech block to permit the

breech block to be forced forwardly against the firing pins by the firing hammer.

A locking means is also provided on the breech block for engaging the firing pin head after it has been rotated to the released position with respect to the receiver head to prevent rotation of the firing pin head during its rearward and forward movement. This locking means is automatically released when the firing pin head is returned to its forward position within the receiver head to provide for the locking rotation of the firing pin head. Suitable keys mounted on the jacket of the weapon also cooperate with slotted keyways provided in the breech block to prevent rotation of the breech block during its rearward and forward sliding movement.

The magazine comprises a plurality of tubes, one for each barrel, which are fixedly secured within the weapon in alignment with the barrels and are adapted to each receive a plurality of cartridges in end to end relation therein. A second set of tubes attached to a common end plate member are telescopically received within the first mentioned tubes and provide for closing the magazine at the rear or butt end of the weapon. The second mentioned tubes and the end plate member are readily removed as a unit to provide for reloading the magazine. A compressible spring is mounted in each of the removable tubes and provides for successively advancing the cartridges to a forward position where they are picked up by the firing pin head during its reloading movement.

To provide for initial loading of the weapon after one supply of cartridges contained in the magazine has been completely used and a fresh supply has been inserted in the magazine, a hand operated member is attached to the breech block and extends laterally outwardly of the weapon through a suitable longitudinal slot and provides for manually pulling the breech block and firing pin head rearwardly in a manner similar to the rearward movement of these parts under the automatic recoil action. The head thus picks up a fresh cartridge for each of the barrels, and these cartridges are loaded into the barrels by action of the compression spring in the manner hereinabove described in connection with the automatic operation. The hand operated member also provides for unloading a loaded firearm, if desired, the extractors and ejectors operating in the same manner as with automatic recoil operation. A friction brake means is also provided in the weapon adjacent the receiver ring and operates upon the receiver ring to cushion the forward return movement of the barrels and ring after recoil operation, and also to lock the ring in its forward position during hand loading or unloading by engagement of the above described lug 64 with the notch 65 of the ring.

A recoil operated firearm is thus provided which may be made relatively light in weight, which is positive in action, and which has a firing power and destructive effect much greater than other firearms of comparable size and weight. The plurality of simultaneously fired projectiles provide greatly increased target coverage while the barrels provide close control over the target pattern. Fig. 36 diagrammatically illustrates the manner in which the barrels control the projectiles to give a desired pattern at a desired range.

While the invention has been illustrated in connection with a revolver or side arm type of firearm, the mechanism as disclosed, and the basic

principles of operation thereof, may be incorporated within a weapon of any desired type. Thus the exact mechanism illustrated could be utilized in a rifle adapted to be fired from the shoulder. In like manner, the disclosed mechanism or slight modifications thereof could be incorporated in an anti-aircraft or anti-tank weapon or any other gun of desired size and type.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. A firearm comprising a barrel, a rotatably and slidably mounted firing pin head, said head being provided with a longitudinal opening extending entirely therethrough, said opening being of a size permitting passage of a cartridge therethrough, magazine means for holding a plurality of cartridges and supporting a cartridge substantially in alignment with said barrel and in a position to be received through said opening, recoil operated means for effecting rotary and sliding movement of the firing pin head, and means on said head in operative relation with said recoil operated means for loading cartridges received through said opening into said barrel under action of said recoil means, said head having a firing pin arranged therein in operative relation with a cartridge loaded into said barrel, said recoil operated means providing for rotating the firing pin head to move said opening into alignment with said barrel and a cartridge supported by said magazine means during loading and to move the opening out of alignment with said barrel after loading thereof.

2. A firearm comprising a plurality of barrels, a firing pin head common to all of said barrels, said firing pin head having a plurality of longitudinal openings extending entirely therethrough, there being one opening for each barrel and of such size as to permit passage of a cartridge therethrough, magazine means for supporting cartridges in position to be received through each of said openings, recoil operated means for actuating said firing pin head to effect loading of said barrels from said magazine means, and means on said head in operative relation with said recoil operated means for loading cartridges received through said openings into each of said barrels under operation of said recoil means, said head having a plurality of firing pins arranged therein in operative relation respectively with cartridges loaded into said barrels.

3. A firearm comprising a plurality of barrels, a rotatably and slidably mounted firing pin head common to all of said barrels, said firing pin head having a plurality of longitudinal openings extending entirely therethrough, there being one opening for each barrel and of such size as to permit passage of a cartridge therethrough, magazine means for supporting cartridges in position to be received through each of said openings, recoil operated means for actuating said firing pin head to effect loading of said barrels from said magazine means, means on said head for loading cartridges received through said openings into each of said barrels under operation of said recoil means, a firing pin for each barrel mounted in said head between said openings, said recoil operated means providing for rotating said firing pins into alignment with said barrels after loading of the barrels and for rotating said openings

into substantial alignment with the barrels upon firing of the firearm, and means for operating said firing pins to effect substantially simultaneous firing of all of said barrels.

4. A firearm comprising a plurality of barrels, a rotatably and slidably mounted firing pin head common to all of said barrels, said firing pin head having a plurality of longitudinal openings extending entirely therethrough, there being one opening for each barrel and of such size as to permit passage of a cartridge therethrough, magazine means for supporting cartridges in position to be received through each of said openings, recoil operated means for actuating said firing pin head to effect loading of said barrels from said magazine means, means on said head for loading cartridges received through said openings into each of said barrels under operation of said recoil means, a firing pin for each barrel mounted in said head between said openings, said recoil operated means providing for rotating said firing pins into alignment with said barrels after loading of the barrels and for rotating said openings into substantial alignment with the barrels upon firing of the firearm, a slidably mounted breech block arranged rearwardly of said firing pin head and adapted to strike each of said firing pins to effect substantially simultaneous firing of said barrels, and trigger controlled means for moving said breech block into striking engagement with the firing pins.

5. A firearm comprising a plurality of barrels, a rotatably and slidably mounted firing pin head common to all of said barrels, said firing pin head having a plurality of firing pins arranged therein in operative relation with said barrels, respectively, a slidably mounted breech block arranged in rear of said firing pin head, said firing pin head and breech block being adapted to move rearwardly under recoil action of the firearm, said breech block and said firing pin head each having a plurality of longitudinal openings extending entirely therethrough, there being one opening for each barrel and of such size to permit passage of cartridges therethrough, the openings in said breech block being arranged in substantial alignment with the barrels, magazine means for supporting cartridges in substantial alignment with each of the barrels and said openings in the breech block, means for returning the breech block and firing pin head to a forward firing position after rearward movement under said recoil action, means on said firing pin head in operative relation with said last mentioned means for loading cartridges from said magazine means into each of the barrels upon said return movement of the firing pin head, and means interconnecting the breech block and firing pin head for rotating the openings in the head into substantial alignment with the barrels and the openings in the breech block upon rearward movement of the breech block and for rotating the openings in the firing pin head out of alignment with the barrels after loading thereof by the firing pin head.

6. A firearm comprising a plurality of barrels, a rotatably and slidably mounted firing pin head common to all of said barrels, a slidably mounted breech block arranged in rear of said firing pin head, said firing pin head and breech block being adapted to move rearwardly under recoil action of the firearm, said breech block and said firing pin head each having a plurality of longitudinal openings extending entirely therethrough, there being one opening for each barrel and of such size

to permit passage of cartridges therethrough, the openings in said breech block being arranged in substantial alignment with the barrels, magazine means for supporting cartridges in substantial alignment with each of the barrels and said openings in the breech block, means for returning the breech block and firing pin head to a forward firing position after rearward movement under said recoil action, means on said firing pin head in operative relation with said last mentioned means for loading cartridges from said magazine means into each of the barrels upon said return movement of the firing pin head, a firing pin for each barrel mounted in said head between said openings, means interconnecting the breech block and firing pin head for rotating the openings in the head into substantial alignment with the barrels and the openings in the breech block upon rearward movement of the breech block and for rotating said firing pins into alignment with the barrels after loading thereof by the firing pin head, and means including a slideable hammer block engageable with the breech block for causing the breech block to strike against said firing pins to effect substantially simultaneous firing of said barrels.

7. A firearm comprising a barrel, a rotatably and slidably mounted firing pin head, a slidably mounted breech block arranged in rear of said firing pin head, said firing pin head and breech block being adapted to move rearwardly under recoil action of the firearm, said breech block and said firing pin head each having a longitudinal opening extending entirely therethrough, said openings being of a size permitting passage of a cartridge therethrough and the opening in said breech block being arranged in substantial alignment with said barrel, magazine means for holding a plurality of cartridges and supporting a cartridge in substantial alignment with the barrel and said opening in the breech block, means for returning the breech block and firing pin head to a forward firing position after rearward movement under said recoil action, means on said firing pin head in operative relation with said last mentioned means for loading a cartridge from said magazine means into said barrel upon said return movement of the firing pin head, said firing pin head having a firing pin therein arranged in operative relation with a cartridge loaded into said barrel, means for rotating said opening in the head into and out of alignment with said barrel and the opening in said breech block, and latch means cooperating between said breech block and said firing pin head for maintaining the opening in said firing pin head in substantial alignment with the opening in said breech block during said loading operation.

8. A firearm comprising a barrel, a rotatably and slidably mounted firing pin head, a slidably mounted breech block arranged in rear of said firing pin head, said firing pin head and breech block being adapted to move rearwardly under recoil action of the firearm, said breech block and said firing pin head each having a longitudinal opening extending entirely therethrough, said openings being of a size permitting passage of a cartridge therethrough and the opening in said breech block being arranged in substantial alignment with said barrel, magazine means for holding a plurality of cartridges and supporting a cartridge in substantial alignment with the barrel and said opening in the breech block, means for returning the breech block and firing pin head to a forward firing position after rear-

ward movement under said recoil action, means on said firing pin head in operative relation with said last mentioned means for loading a cartridge from said magazine means into said barrel upon said return movement of the firing pin head, means for rotating said opening in the head into and out of alignment with said barrel and the opening in said breech block, stop means providing a spacing between said breech block and said firing pin head upon return movement of the block and head, a firing pin mounted in said firing pin head, and trigger operated means for releasing said stop means and causing said breech block to strike said firing pin to fire the barrel.

9. A firearm comprising a barrel, a rotatably and slidably mounted firing pin head, a slidably mounted breech block arranged in rear of said firing pin head, said firing pin head and breech block being adapted to move rearwardly under recoil action of the firearm, said breech block and said firing pin head each having a longitudinal opening extending entirely therethrough, said openings being of a size permitting passage of a cartridge therethrough and the opening in said breech block being arranged in substantial alignment with said barrel, magazine means for holding a plurality of cartridges and supporting a cartridge in substantial alignment with the barrel and said opening in the breech block, means for returning the breech block and firing pin head to a forward firing position after rearward movement under said recoil action, means on said firing pin head in operative relation with said last mentioned means for loading a cartridge from said magazine means into said barrel upon said return movement of the firing pin head, means for rotating said opening in the head into and out of alignment with said barrel and the opening in said breech block, stop means providing a spacing between said breech block and said firing pin head upon return movement of the block and head, a firing pin mounted in said firing pin head, a spring pressed hammer means, latch means for retaining said hammer means in a firing position, and trigger operated means for releasing said hammer retaining means and said stop means for causing said breech block to strike said firing pin to fire the barrel.

10. A firearm comprising a barrel, a rotatably and slidably mounted firing pin head, a slidably mounted breech block arranged in rear of said firing pin head, said firing pin head and breech block being adapted to move rearwardly under recoil action of the firearm, said breech block and said firing pin head each having a longitudinal opening extending entirely therethrough, said openings being of a size permitting passage of a cartridge therethrough and the opening in said breech block being arranged in substantial alignment with said barrel, magazine means for holding a plurality of cartridges and supporting a cartridge in substantial alignment with the barrel and said opening in the breech block, means for returning the breech block and firing pin head to a forward firing position after rearward movement under said recoil action, means on said firing pin head in operative relation with said last mentioned means for loading a cartridge from said magazine means into said barrel upon said return movement of the firing pin head, means for rotating said opening in the head into and out of alignment with said barrel and the opening in said breech block, stop means providing a spacing between said breech block and said

firing pin head upon return movement of the block and head, a firing pin mounted in said firing pin head, a spring pressed hammer means, latch means for retaining said hammer means in a firing position, and trigger operated means for releasing said hammer retaining means and said stop means for causing said breech block to strike said firing pin to fire the barrel, said hammer means comprising a sliding block returned to latched firing position by rearward movement of said breech block under said recoil action.

11. A firearm comprising a barrel, rotatably and slidably mounted firing pin head, a slidably mounted breech block arranged in rear of said firing pin head, said firing pin head and breech block being adapted to move rearwardly under recoil action of the firearm, said breech block and said firing pin head each having a longitudinal opening extending entirely therethrough, said openings being of a size permitting passage of a cartridge therethrough and the opening in said breech block being arranged in substantial alignment with said barrel, magazine means for holding a plurality of cartridges and supporting a cartridge in substantial alignment with the barrel and said opening in the breech block, means for returning the breech block and firing pin head to a forward firing position after rearward movement under said recoil action, means on said firing pin head in operative relation with said last mentioned means for loading a cartridge from said magazine means into said barrel upon said return movement of the firing pin head, means for rotating said opening in the head into and out of alignment with said barrel and the opening in said breech block, stop means providing a spacing between said breech block and said firing pin head upon return movement of the block and head, a firing pin mounted in said firing pin head, a spring pressed hammer means, latch means for retaining said hammer means in a firing position, and trigger operated means for releasing said hammer retaining means and said stop means for causing said breech block to strike said firing pin to fire the barrel, and means preventing further operation of said trigger operated means until the breech block and firing pin head is again in position for firing.

12. A firearm comprising a plurality of barrels disposed circularly, a plurality of magazine tubes, one for each barrel, in position to deliver cartridges successively at delivery stations, each in line with a corresponding barrel, transfer means reciprocable between said stations and the facing ends of said barrels for loading all the barrels simultaneously with cartridges transferred from said stations and trigger actuated means operable to detonate said cartridges simultaneously in said barrels.

13. A firearm comprising a plurality of barrels, magazine feed means operable to present a cartridge in alignment with each of said barrels, and means for transferring the so presented cartridges simultaneously each to loaded position in a corresponding barrel comprising recoil operated means reciprocable between said magazine means and said barrels, said recoil operated means comprising a block formed with openings positionable in alignment with said barrels to permit delivery of said cartridges through said openings in loading said barrels, said block carrying firing pins offset from said openings and being shiftable to present said firing pins in firing position with respect to cartridges in said barrels, and trigger controlled means for actuating

said firing pins to detonate said cartridges simultaneously in said barrels.

14. A firearm comprising a barrel, a magazine tube in position to deliver cartridges in succession to a delivery station in alignment with said barrel, means reciprocable between said station and said barrel for transferring a cartridge from the station and loading it in the barrel, said means comprising a member having a cartridge transfer opening in alignment with said barrel to permit delivery of the cartridge therethrough in loading the barrel, said member having a firing pin offset from said opening and being shiftable to align the firing pin with a cartridge in the barrel, and trigger means actuating the firing pin to detonate the cartridge.

15. A firearm comprising a barrel, magazine means in position to deliver cartridges in succession to a delivery station in alignment with said barrel, recoil operated means reciprocable between said delivery station and said barrel for transferring a cartridge from the station and loading it in the barrel, said means comprising a member having a cartridge transfer opening therethrough, and an offset firing pin, and means actuated by the reciprocating movement of the recoil operated means for rocking said member to alternately dispose said transfer opening and said firing pin in alignment with said barrel, and trigger means for actuating said firing pin to detonate a cartridge in the barrel.

16. A firearm comprising a plurality of barrels, magazine feed means operable to present a cartridge in alignment with each of said barrels, means for transferring the so presented cartridges each to loaded position in a corresponding barrel comprising a recoil operated member reciprocable between said magazine means and said barrels, a firing pin block formed with openings permitting delivery of said cartridges therethrough in loading said barrels, firing pins mounted in said block intermediate said openings, means operable to rock said block on said member to alternately position said openings and said firing pins in alignment with said barrels, and trigger controlled means for actuating said firing pins to detonate cartridges in said barrels.

17. A firearm comprising a plurality of barrels supported for limited longitudinal movement

under recoil action, a receiver head interconnecting the breech ends of said barrels, magazine means in axial alignment with said barrels, a firing pin head, common to all of said barrels and mounted at the breech ends thereof, said firing pin head being retractable longitudinally from the breech ends of said barrels and reciprocable between said magazine means and said receiver head to deliver cartridges from said magazine means to the breech ends of said barrels, means for releasably locking said firing pin head to said receiver head, trigger responsive firing pins on said head for detonating said cartridges in said barrels, and recoil operated means for unlocking said firing pin head from the receiver head and retracting the same longitudinally from the receiver head to eject cartridge shells from said barrels and to reload said barrels with cartridges from said magazine means.

ERNEST C. NEAL.
